ABSTRACT OF THE DISCLOSURE

An electronic circuit having a pulse generating circuit for applying ionizing pulses to a fluorescent lamp which draws discharge current from an alternating current supply, and a transformer connected to the supply for boosting the alternating current applied to the lamp.

Conventional fluorescent lamp starting and operating circuits have comprised a ballast for applying a high starting voltage to the lamp to ionize it and start discharge and for inductively limiting current through the ionized lamp. Because of the weight and bulk of the ballast and its high expense, heating and noise, control circuits have been proposed which start and control the lamp discharge by various electronic switching circuits. Some of the advanced electronically valved circuits comprise pulse generating or gating means for periodically applying a voltage pulse to the lamp thereby ionizing the lamp sufficiently to support an arc discharge for a limited period, usually a half-cycle or less of the alternating current supply. Because standard lamps and operating circuits are designed for about 110 volt operation at least, they may fail to operate properly if the alternating current supply voltages drop much below 110 volts. Unlike ballast circuits which apply an ionizing voltage well above that required for continuous operation, ionizing pulse generation circuits limit the amount of ionization and the amplitude of the ionizing pulses and are adversely affected by line voltage drops.

It is the object of the present invention to provide an electronic pulsing circuit of the type described above with means for insuring that the ionizing discharge voltage is adequate for continuous operation of the lamp.

According to the invention an arc discharge lamp operating circuit comprises discharge terminals for connection to the lamp, power terminals for connection to a supply of alternating current, a power circuit connecting said power terminals to said discharge terminals including means for applying periodic voltage pulses to said discharge terminals thereby to support an arc discharge by ionization in the lamp and to draw current from said alternating current supply, and a transformer having a primary connected between said power terminals and a secondary connected between one power terminal and one lamp terminal, said primary and secondary being connected such that current in said primary induces current in said secondary substantially in phase with the supply current in said secondary.

For the purpose of illustration typical embodiments of the invention are shown in the accompanying drawing, in which

FIG. 1 is a schematic diagram of a fluorescent lamp operating circuit according to the invention.

The operating circuit of FIG. 1 comprises discharge terminals *l* between which are connected two four foot HO lamps *L* which may be considered as a single lamp. Power for the lamps is supplied from 115 volt, 60 cycle alternating current terminals *A* and *C*. Power terminal *A* is connected to a lamp terminal *l* through an autotransformer primary *T1* and secondary *T2* having a turns ratio

2

of 1 to 10 and negligible reactance. Power terminal *C* is connected to a lamp terminal *l* through the secondary *T4* of a core transformer having a primary *T3*. The core transformer has a turns ratio of 12 in the primary to 1 in the secondary and is hence a step-down transformer. The primary *T3*, being connected across the 120 volt power terminals *A* and *C*, induces about 10 volts in the secondary in phase with line current in the secondary, thereby boosting the RMS value of voltage applied to the lamp. The core transformer reactance is of negligible reactance, e.g. less than 100 ohms, compared to a conventional ballast.

A voltage pulse discharging circuit includes a triac *V1* (G.E. type SC45B), a diac *D1* (G.E. type ST2), a primary voltage pulse storage capacitor *C1* (6 microfarad) 15 a secondary storage capacitor *C2* (0.33 microfarad) and a coupling capacitor *C3* (0.07 microfarad). The primary storage capacitor *C1* and triac *T1* are connected in series between the power terminals *A* and *C* through the autotransformer primary *T1*, so that during each half-cycle of alternating current the primary storage capacitor *C1* charges, through the triac *T1*. In the succeeding half-cycle the voltage across the secondary capacitor *C2* rises toward the breakdown voltage of the diac *D1*. When this breakdown voltage is exceeded the diac *D1* conducts allowing the secondary capacitor *C2* to discharge to the gate electrode *g* of the triac and trigger the triac into avalanche conduction. The primary capacitor then discharges through the triac and autotransformer primary and reverses its charge. The discharge voltage is stepped up by 20 the 1 to 3 ratio of primary to secondary, and the stepped up voltage (e.g. 300 volts peak) is applied to the lamp terminals *l*. At this instant a limited number of ions are established in the lamps *L*, and the lamps fully ignite and conduct line current for part or all of the half-cycle. About 25 when the line voltage passes through zero the arc tends to extinguish depending on the amplitude and duration of the ionizing pulse. If the line voltage drops, the amplitude of the ionizing pulse will drop and the lamps may be insufficiently ionized to start discharge or to maintain discharge until the next pulse is applied. The lamps might 30 therefore fail to ignite, extinguish intermittently or flicker objectionably.

According to the present invention the core transformer *T3*, *T4* adds a small increment of voltage to the ionizing pulse and to the open circuit voltage applied to the lamps. With one to twelve turns ratio the transformer adds an increment of one-twelfth the line voltage, about ten volts, which is adequate to maintain the voltage for which the 35 lamps and pulsing circuit are designed with expected drops of line voltage, and yet does not increase the ionizing pulse peak voltage so much as to excessively ionize the lamp at or expectably above normal line voltage. The transformer *T3*, *T4* thus substantially increases the reliability of the 40 operating circuit.

While one desirable embodiment of the invention has herein been disclosed by way of example, it is to be understood that the invention is broadly inclusive of any and all modifications falling within the terms of the appended 45 claims.

I claim:

1. An arc discharge lamp operating circuit comprising: discharge terminals for connection to the lamp, power terminals for connection to a supply of alternating current, a power circuit connecting said power terminals to said discharge terminals, and means outside said power circuit for storing and applying periodic voltage pulses to said discharge terminals superimposed on said supply current thereby to support an arc discharge by ionization in the lamp and to draw current from said alternating current supply, and

a transformer of negligible reactance having a primary connected across said power terminals and a secondary connected between one power terminal and one lamp terminal, the windings of said primary and secondary being connected in additive voltage phase, whereby alternating supply current in said primary induces current in said secondary substantially in phase with and in increase of the supply current in said secondary from said supply terminals.

2. A circuit according to claim 1 wherein said transformer has a step-down turns ratio.

3. A circuit according to claim 1 wherein the secondary to primary turns ratio of said transformer is a minor fraction.
